UNITED STATES PATENT OFFICE

HARRY E. BROWN, OF WICHITA, KANSAS, ASSIGNOR TO ALBERT H. NEILSON, OF TULSA,
OKLAHOMA

GRAB FOR DRILL RODS AND THE LIKE

Application filed May 3, 1929. Serial No. 360,924.

This invention relates to a grab designed primarily for lifting broken rods from the inside of well tubing, one of the objects of the invention being to provide a grab which can be used in connection with rods of different diameters, the grab being simple and compact in construction and constituting means for firmly gripping the rod with which it is placed in engagement.

10 Another object is to provide a structure of this character having means for engaging a collar or joint on a rod if conveniently located, thereby to provide a supplemental rod engaging means to insure elevation of the 15 rod from a well.

Another object is to provide a tool of this character having means combined therewith whereby a broken rod can be engaged and picked up.

20 A further object is to so construct a circular guide casing for the grab as to properly resist strains without unduly adding to the size or weight of the tool, the wall of the structure being thickened where necessary and being of reduced thickness where the strains are the least.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the 35 scope of what is claimed without departing from the spirit of the invention.

In the accompanying drawings the preferred form of the invention has been shown.

In the said drawings,

40 Figure 1 is a central longitudinal section through the tool.

Figure 2 is a front elevation of the latch portion thereof.

Figure 3 is a section on line 3—3, Figure 2.

Figure 4 is a section on line 4—4, Figure 1.

Fig. 5 is a section on the line 5—5, Figure 1.

Figure 6 is a section on line 6—6, Figure 2.

Figure 7 is a section on line 7—7, Figure 1.

Referring to the figures by characters of reference, 1 designates the elongated head

of the tool, the same being provided at one end with a threaded stud 2 for engagement with a rod used for manipulating the tool. The upper portion of the head is formed with opposed depressions 3 for the purpose of lightening the tool without reducing the strength thereof. A longitudinal bore 4 is extended into the tool from the lower end thereof and has a counterbore 5 extending therefrom into the reduced portion of the head. The wall of the bore 4 is cut away to provide diametrically opposed slots 6 and below these slots the wall of the bore is contracted and formed with opposed grooves 7 the inner walls of which converge downwardly and terminate at a throat 8 from which the wall is flared to the end of the head as shown at 9.

Slidably mounted within the bore 4 is a controlling head 10 from which projects a stem 11 located within the counterbore 5. A coiled spring 12 is located in the counterbore and extends around the stem 11, one end of this spring bearing against the end of the counterbore while the other end bears against the controlling head 10. An opening 13 is extended diametrically through the head 10 and is adapted, when said head is thrust upwardly within the head 1, to register with openings 14 formed in the wall of the counterbore 5. When thus located, a pin P can be inserted through the aligning openings 13 and 14 for the purpose of holding the head 10 elevated and the spring 12 under compression.

Extending through the head 10 is a bolt 15 to the ends of which are connected arms 16 that extend upwardly from substantially wedge-shaped slips 17, the inner faces of which are toothed as shown at 18. The slips 17 are seated in the opposed grooves 7.

Stop studs 19 are extended from the wall of the bore 4 at diametrically opposed points and project into the path of the controlling head 10 so as to limit its movement under the action of the spring 12.

A guide socket or tube 20 is extended from the lower portion of the head 1 as shown and has its wall cut away to provide a relatively broad slot 21 for the reception of the one-

piece latch 22. The side walls of this slot converge adjacent the lower ends thereof where bearing shoulders 23 are provided from which said walls extend downwardly as at 24 and merge into the walls of laterally extending recesses 25 that are preferably rounded as shown. As shown in Figure 3, the portions 21 and 24 of the walls of the slot are disposed in substantially parallel planes. This slot 21 is adapted to receive the latch 22 preferably of the construction illustrated, the said latch including a transversely bowed head 26 the width of which is slightly less than the distance between the inner edges of the walls 23. A tongue 27 is extended downwardly from the head and has laterally extending rounded projections 28 adapted to fit within the recesses 25. The lower end of the tongue is adapted to bear against the bottom wall 29 of the slot which thus forms a bearing for the latch. It will be noted that the bottom edge of the tongue is inclined downwardly and inwardly whereas the edge 29 forming the wall of the slot is inclined upwardly and outwardly. A lap is thus provided which prevents the latch from shifting outwardly from its proper engagement with the socket or tube 20. A spring 30 is secured to the outer face of the socket 20 and bears against a flat surface 37 on the head 26 so as to hold the head normally pressed inwardly as shown.

The upper end of the latch 22 is concaved from side to side to provide an end recess 38 and the wall of this recess is beveled to an edge 39.

As shown in Figure 1, the wall of the socket 20 can be thickened where the slot 21 is provided, thus to properly strengthen the socket and hold it against collapsing when subjected to severe strain.

Formed within the socket member 20 above a point diametrically opposite the slot 21 is a longitudinal slot 40 in which is slidably mounted the head 41 of a stud 42 which is located within the upper portion of an arcuate block or slip 43 which is inserted upwardly into the socket member 20 and thereafter held in place by screwing the stud 42 thereinto. The slip extends back of the latch 22 and has its lower end beveled as shown at 44 so as to constitute deflecting means. The inner surface of the slip or block is curved inwardly and terminates in a shoulder 45. The side edges of the block are formed with angular recesses 46 and these sides are adapted to be slidably engaged by the sides of the latch 22 when said latch is pressed toward the slip 43. The upper walls of the recesses 46 normally overhang the sides of the upper ends of the latch.

In using this tool for the purpose of extracting broken rods the controlling head 10 is released so as to rest upon the lug or stud 19 and the tool is then lowered into the well.

If a collar or coupling is located at the upper end of the broken rod the same will be received within the socket 20 and as the latch 22 moves downwardly past the collar or coupling, it will be forced outwardly against the action of spring 30 until the upper end of the latch passes below the collar or coupling. At that time it will be forced back by spring 30 so as to assume a position astride the rod and under the collar or coupling. The collar or other enlargement in the rod will become seated on the shoulder 45. Thus when the tool is pulled upwardly the rod will be carried therewith, the weight of the rod being supported by the latch and by the shoulder 45. If the broken rod is not provided with a collar or coupling at its upper end the slip or block 43 is removed and the rod will be received between the slips 17 as the tool is lowered. The frictional engagement of the rod with the slips will force them upwardly and apart against the action of the spring 12. As the rod is brought to position well within the bore 4 the tool is pulled upwardly. This will result in the teeth gripping opposed portions of the rod, the spring 12 forcing the slips downwardly upon the converging walls of the slots or grooves 7 so that the rod will be tightly held and will be drawn upwardly with the tool.

Importance is attached to the fact that the slips can be held up by inserting a nail, pin or the like through the openings 13 and 14 so that the slips will be out of the way when the latch 22 is used for pulling a rod as hereinbefore described.

As this latch is subjected to severe strains during the pulling operation it is essential that the same be provided with the greatest possible bearing surface. For this reason the arrangement of the bearing shoulders 24, the bearing projections 28 and the recesses 25 as well as the lapping bearings 29 are of considerable importance.

By mounting the spring 30 as shown it can be swung laterally to allow a latch to be readily placed in or removed from position.

Adjacent and above the latch 27 the wall of the socket 20 is gradually thickened as shown particularly in Figures 1, 3 and 6 so that when an engaged rod or the like is thrust transversely against the slip 43 because of its engagement with the latch 22, there will be no danger of said wall bending under the strains to which it has been subjected. At other points where the socket is not subjected to excessive strains the wall is of minimum thickness.

By mounting the spring 30 on a pivot as shown it is possible to swing the same away from the opening in which the latch 22 is seated so that a new latch can easily be placed in position when desired.

While this device is particularly useful

for removing broken and parted rods, it can also be used advantageously for grabbing and lifting tools, sections, or parts of well casings, etc.

5 The upper and lower portions of the device are used in one tool and lowered simultaneously so that should it be impossible to grab the broken or separated part with one portion of the tool the other portion would be in position for engaging and lifting the part.

10 What I claim and desire to secure by Letters Patent is:

15 1. A tool of the class described, including a socket member having a lateral opening and superposed bearing portions, and a latch mounted for pivotal movement in said opening having superposed bearing portions cooperative with the bearing portions on the 20 socket to provide a multiple support for the latch and a load carried by the latch.

25 2. A tool of the class described, including a socket member having a lateral opening and superposed upwardly facing bearing portions in said opening, a latch pivotally mounted in said opening having downwardly facing bearing portions cooperative with the bearing portions on the socket to provide a 30 multiple support for the latch when subjected to downward pressure of a load supported by the latch, and means yieldingly urging the latch into the socket.

35 3. A tool of the class described including a head, spring controlled gripping slips movably mounted therein, a tubular socket member depending from the head, there being a slot therein, said slot having oppositely extending sockets, a latch movably supported within the slot and having laterally extending projections mounted for movement within the socket, the bottom wall of the slot constituting a bearing for the lower end of the latch, there being shoulders extending laterally from the side portions of the latch and shoulders at the sides of the slot, all of the 40 shoulders cooperating to support the latch when subjected to the weight of a load, and yieldingly means for holding the latch normally pressed inwardly relative to the socket member.

45 4. In a tool of the class described the combination with a head, of a socket member projecting therefrom and having a slot in the wall thereof, a spring controlled means in the slot pivotally connected to and normally projecting into the socket member, and a slip within the socket member, said slip and spring controlled means cooperating to grip and support a rod insertable into the socket member.

50 5. In a tool of the class described a socket member having a slot, a slip removably mounted in the socket member and having a shoulder, a latch mounted to swing within the slot, and yieldingly means for holding the

latch normally pressed toward the slip, said latch and slip cooperating to engage and support an inserted rod.

55 6. The combination with a socket member having a slot, of a slip removably mounted in the socket member and having a shoulder, there being opposed recesses in the edge portions of the slip, a latch pivotally mounted in the slot, and yielding means for holding the latch normally pressed against the recessed edges of the slip, thereby to hold the slip within the socket member, said latch and slip cooperating to engage and support a rod inserted therebetween.

70 7. A tool of the class described including a socket member having a slot, of a latch pivotally mounted in said slot having a recess provided with a knife edge for straddling and biting into an object to be lifted, and a slip cooperating with the latch and in the socket member for engagement by the said object when subjected to the action of the latch.

75 8. In a tool of the class described a socket member having a slot, the wall of said member being thickest in the vicinity of the slot, the side walls of the slots merging into the walls of laterally extended rounded recesses within the socket member, a latch in the slot, rounded projections upon the latch seated within said recesses in the socket thereby to provide a hinged connection between the latch and socket, said latch and projections being movable bodily into the slot and recesses respectively, a spring secured to the socket and bearing against the latch to hold the free end thereof normally pressed into the socket, and a slip in the socket for engagement by the latch.

90 9. In testimony that I claim the foregoing as my own, I have hereto affixed my signature.
